UNITED STATES PATENT OFFICE.

HERBERT HOWARD, OF GALENA, OHIO.

COMBINATION CURRYCOMB AND BRUSH.

No. 862,918.

Specification of Letters Patent.

Patented Aug. 13, 1907.

Application filed August 16, 1906. Serial No. 330,853.

To all whom it may concern:

Be it known that I, HERBERT HOWARD, a citizen of the United States, residing at Galena, in the county of Delaware and State of Ohio, have invented a new and useful Improvement in a Combination Currycomb and Brush, of which the following is a specification.

This invention relates to combination curry comb and brushes, the object being to provide very novel means for connecting the comb and brush so that they can be used alternately, or disconnected and used separately when desired.

Another object of my invention is to provide very novel means for adjusting the handle so that it can be turned so as to be above the back of the curry comb or brush as the case may be.

With these objects in view, the invention consists in the novel features of construction, hereinafter fully described and pointed out in the claims.

In the drawings forming a part of this specification:—
20 Figure 1 is a perspective view of my improved combination curry comb and brush. Fig. 2 is a side elevational view of the comb and brush showing the handle in sections and part of the brush in section. Fig. 3 is a detail view of the plate. Fig. 4 is a top plan view of the brush partly broken away showing the connecting bolts in section.

Referring to the drawing A, indicates an ordinary curry comb, to one end of which are secured blocks A', to which is secured a plate B having an upwardly projecting portion B', provided with an opening in which a rod C², is mounted which extends out from an arm C', carried by the ferrule C. The other end of the rod is mounted in an opening in an angle plate D, secured to the other end of the comb. A handle, E is secured in the ferrule provided with a longitudinal bore E', enlarged at its outer end in which a coil spring F, is arranged. Extending through said bore and spring is a rod G, having a head G', at its outer end which is engaged by the outer end of the spring F. The other end is reduced and provided with a square head G², adapted to be held by the coil spring in one of the square openings B³, formed at the ends of the semi-circular groove B², formed in the upwardly projecting portion of the plate.

45 Bolts H, project upwardly from the back of the comb upon which nuts H', are arranged, adapted to engage enlarged nuts H², which are adapted to engage the brush

I, arranged thereon, the other end of the brush resting on the angle plate D. The end of the bolt H, project up through the elongated openings I', formed therein and are provided with oblong nuts H³, which are adapted to be turned cross-wise of the opening I', so as to securely lock the brush between the nuts H², H³.

When it is desired to use either the brush or comb, the head G', of the rod G, is pushed in so as to throw the square head out of the opening and bring the reduced portion of the rod in the groove. The handle is then turned so as to bring the handle above the back of the brush or comb, as the case may be, so that it can be readily used.

Having thus fully described my invention, what I claim as new and desire to secure by Letters Patent is:—

1. In a device of the kind described, the combination with a comb, of apertured plates secured to said comb, a brush carried by said comb and a handle adjustably mounted in said plates, for the purpose described.

2. In a device of the kind described, the combination with a comb, of plates secured to said comb, a rod mounted on said plate, provided with an arm, a handle secured to said arm, and a brush detachably connected to the comb, for the purpose described.

3. In a device of the kind described, the combination with a comb and brush secured together, of a handle adjustably connected thereto, and locking means carried by the handle, for the purpose described.

4. In a device of the kind described, the combination with a comb apertured plates secured to said comb, a brush connected to said comb, a handle provided with a rod mounted in said plates and means for locking said handle, for the purpose described.

5. In a device of the kind described, the combination with a comb, of a plate secured to one end of said comb, having a semi-circular groove formed therein and provided with square openings at its ends, a rod mounted in said plate provided with an arm, a handle secured to said arm, and a spring actuated rod mounted in the handle provided with a square head adapted to fit in one of the square openings in said plate, for the purpose described.

6. In a device of the kind described, the combination with a comb having a brush detachably connected thereto, of an apertured plate secured to said comb provided with a semi-circular groove having square openings formed in its ends, a rod mounted in said plate, provided with an arm, a handle secured to said arm, a spring actuated rod carried by the handle provided with a square head adapted to fit in the openings at the end of the groove in the plate, for the purpose described.

HERBERT HOWARD.
